UNITED STATES PATENT OFFICE.

HENRY W. DIECK, OF BROOKLYN, NEW YORK, ASSIGNOR TO THE STANDARD TEXTILE PRODUCTS COMPANY, OF NEW YORK, N. Y., A CORPORATION OF OHIO.

DESIGN FOR A TABLE COVER OR SIMILAR ARTICLE.

Application filed September 22, 1927. Serial No. 23,504. Term of patent 3½ years.

To all whom it may concern:

Be it known that I, HENRY W. DIECK, a citizen of the United States, residing in the borough of Brooklyn, county of Kings, and State of New York, have invented a new, original, and ornamental Design for Table Covers or Similar Articles, of which the following is a specification, reference being had to the accompanying drawing, forming part thereof.

The figure of drawing is a view in top plan of a table cover or similar article embodying my new and ornamental design, the figure showing one-half only of the design, the details of the latter terminating at the broken lines, the basic material being shown by full lines, and the extension of the decoration being indicated by dotted lines.

I claim:

The ornamental design for a table cover or similar article, as shown and described.

HENRY W. DIECK.
